CLAIM

The ornamental design for a display screen with graphical user interface as shown and described.

DESCRIPTION

The FIGURE is a front view of a display screen with graphical user interface showing my new design.

Each of the short vertical lines between the “10” and the “50”, the three short vertical lines to the right of the “50”, and the three short vertical lines to the left of the “10” are part of the claimed design. The stippling in the rectangular shapes in the FIGURE indicates a contrast of appearance and does not depict any particular color, texture, or material. The even-length broken line regions illustrating portions of the graphical user interface form no part of the claimed design, including the horizontal even-length broken lines that extend through the claimed rectangular shapes. The uneven-length broken line illustrating a display screen forms no part of the claimed design.
